UNITED STATES PATENT OFFICE.

JAMES MELIO, OF CHICAGO, ILLINOIS.

NON-REFILLABLE BOTTLE.

1,034,721.

Specification of Letters Patent.

Patented Aug. 6, 1912.

Application filed February 15, 1911. Serial No. 608,841.

To all whom it may concern:

Be it known that I, JAMES MELIO, a citizen of the United States of America, and a resident of Chicago, county of Cook, State of Illinois, have invented certain new and useful Improvements in Non-Refillable Bottles, of which the following is a specification.

The main objects of this invention are to provide an improved form of combined valve casing and valve adapted to be supported in the neck of a bottle to render the bottle non-refillable; to provide an improved arrangement of the liquid passages in such devices; to provide improved means for keeping the valve closed until after the bottle is tipped beyond the horizontal to a pouring position; and to provide an improved construction of the bottle neck for supporting and retaining said valve casing therein.

An illustrative embodiment of this invention is shown in the accompanying drawings, in which:—
25 Figure 1 is a sectional elevation of the neck of a bottle in which is supported a valve casing and valve constructed according to this invention. Fig. 2 is a similar view, showing the bottle tipped to a substantially horizontal position, illustrating the action of the valve and weight. Fig. 3 is also a similar view, showing the position to which the bottle must be tipped to unseat the valve for pouring the liquid therefrom. Fig. 4 is a transverse sectional detail taken on the line A—A of Fig. 1. Fig. 5 is a section taken on the line B—B of Fig. 1. Fig. 6 is a fragmentary detail of the upper end of the valve casing, showing 40 the arrangement of the spiral passages therein.

In the construction shown in the drawings, the valve casing comprises a pair of telescoping parts 1 and 2, which are adapted to be supported in the neck of a bottle in the manner shown. The part 2 is provided with a valve seat 3 near its upper end, which coacts with a spherical valve 4 for controlling the passage of liquid 45 through the casing. The top of the valve may be cut away to reduce its weight but the spherical sides should be of sufficient extent to insure tight seating of the valve in any inclined position that it is capable of 50 assuming. The valve 4 is normally held on its seat by a weight 5 depending therefrom

on an integral stem 6. The shoulder 7 of the weight is conical, and is adapted to coact with the annular shoulder 8 for retaining the valve 4 on its seat until the 60 bottle is tipped to such a position that the conical shoulder 7 will slide on the shoulder of the bottle so as to unseat the valve. This does not occur until the bottle is tipped beyond the horizontal to a substantially inverted position. 65

The valve casing is provided with annular shoulders 9 and 10 formed at the opposite ends, by means of which it is supported in the neck of the bottle. The shoulder 9 is 70 tapered, and has a wedging fit with a conical hollow cork 11 and the shoulder 10 is substantially equal in diameter to the interior of the neck and fits snugly therein. Apertures 12 are formed in the part 1 between the valve seat 3 and the partition 13, which partition forms a closure for the upper end of the valve casing. These apertures lead into the space between the bottle neck and the casing, from which a plurality 80 of spiral peripheral passages 14, formed in the shoulder 10, lead to the exterior of the valve casing. 75

The cork 11 is confined in the neck of the bottle between shoulders 15 and 16. The 85 shoulders 16 are arranged in a series around the neck of the bottle, as shown in Fig. 5, and are formed by indenting the exterior 90 of the neck at 17, as shown in Fig. 4, while the shoulder 15 is formed by the annular indenting of the neck at 18. The neck of the bottle is enlarged at 19 between the shoulders 16 and its upper end, so as to provide a suitable space adjacent to the apertures 12 for facilitating the pouring of the 95 liquid.

All of the parts except the cork 11 may be made of glass, and the casing sections 1 and 2 may be cemented together so as to prevent the inner section 2 from being caused to fall 100 into the bottle.

The use and operation of the device is as follows:—After the bottle has been filled with a liquid, the cork 11 is inserted into the neck of the bottle, and by means of a 105 suitable implement is forced into position between the shoulders 15 and 16. The valve sections 1 and 2, after being assembled and cemented together with the valve 4 in place, are then forced into the neck of 110 the bottle until the tapered shoulder 9 is securely wedged into the cork 11 below the

shoulders 16. The shoulder 10 fitting snugly within the neck and the passages 14 being spiral, it is practically impossible for a grip to be obtained with any implement 5 for accomplishing the withdrawal of the casing after it has once been forced into place. When the bottle is in its upright position, the weight 5 normally tends to hold the valve 4 on its seat 3, but when the bottle 10 is tipped, the weight 5 will swing to one side and the conical part 7 will engage with the shoulder 8 and tend to hold the valve 4 on its seat 3 until the bottle has reached a substantially inverted position. The partition 15 then supports the valve in its unseated position, and the liquid flows out through the apertures 12 into the space between the casing and the neck of the bottle, and finally runs out through the spiral passages 14. As 20 soon as the bottle is tilted back, the conical part 7, acting against the shoulders 8, will tend to draw the valve 4 into engagement with the seat 3 and prevent refilling of the bottle by pouring liquid into it when it is 25 inclined.

Although but one specific embodiment of this invention is herein shown and described, it will be understood that some of the details of the construction shown may be altered or omitted without departing from the 30 spirit of this invention, as defined by the following claims.

I claim:

1. A bottle of the class described comprising, a tubular neck having a shoulder at 35 its lower end, a valve casing fitted within said neck at its upper and lower ends and

being spaced away from said neck at its middle portion to provide an annular space around it and being constructed of upper 40 and lower parts telescoping each other, a valve seat in said lower part, a spherical valve coacting with said seat and having a depending stem with a conical weight at its end, said conical weight being adapted to 45 engage said shoulder to cause the seating of said valve when the bottle is tipped, the lower end portions of said valve casing having their outer peripheries substantially flush and in alinement with each other, and 50 a resilient packing ring surrounding said lower end portions of said casing parts and having frictional engagement with both, the material of said bottle neck being indented from the exterior thereof so as to form an 55 annular series of inwardly extending shoulders adapted to overlap said packing ring and prevent the withdrawal thereof.

2. A bottle of the class described comprising a neck, a valve casing mounted therein, 60 a packing ring surrounding said valve casing and having frictional engagement therewith, the neck of said bottle being provided with a series of external indentations so as to form on its inner surface an annular series of shoulders overlapping said packing ring for the purpose specified. 65

Signed at Chicago this 11th day of February 1911.

JAMES MELIO.
